UNITED STATES PATENT OFFICE

2,499,293

SPRING SEAT AND EQUALIZER LIFTING
MEANS.

Martin P. Blomberg, Hinsdale, Ill., assignor to
General Motors Corporation, Detroit, Mich., a
corporation of Delaware

Application April 20, 1946; Serial No. 663,715

4 Claims. (Cl. 105—194)

1

This invention generally relates to railway vehicle trucks and more particularly to improvements in parts thereof whereby the parts may be safely and quickly assembled.

In the assembly and disassembly of trucks of this type the component parts are assembled by a crane and slings attached to the heavier and longer parts. The slings are attached and held in place by two men during lifting by the crane of the longer parts, particularly the equalizer assembly, in order to reduce the natural tendency for the slings to slip and cause injury to the men and damage to the equipment.

The object of the present invention is to provide sling attaching means on the equalizer spring seats whereby one man can attach the sling, step out of the way and direct movement of the equalizer assembly into place in a safe manner and with minimum delay.

The means by which this object is accomplished will become apparent by reference to the following detailed description and drawing illustrating one form of the invention.

Figure 1 of the drawing is a side elevation of a truck equalizer assembly with parts broken away to show details of the invention to better advantage.

Figure 2 is an enlarged plan view taken on line 2—2 of Figure 1 with parts broken away.

Figure 3 is a longitudinal sectional view taken on line 3—3 of Figure 2 with parts broken away.

Figure 4 is a cross sectional view taken on line 4—4 of Figure 3.

Figures 5, 6, 7 and 8 are views similar to Figures 1, 2, 3 and 4 showing a modification of the invention.

As best illustrated in Figure 1 of the drawings the equalizer assembly includes two identical spring seats 1 shown positioned adjacent the ends of the central depressed portion of two equalizer bars 3 in symmetrical relation for helical truck springs. Each spring seat 1, as best illustrated in Figures 2, 3 and 4 of the drawings, is provided with integral upper side supporting projections 5 resting on the upper edges of the bars 3, a lifting hook portion 7 extending longitudinally inwardly from the end of the bars and a central pocket portion 9 for insertion of the lower end of a helical truck spring, not shown. The pocket 9 is provided with side openings 11 and also with a drain hole 13 extending downwardly and outwardly from the pocket along the outer leg of a bifurcated body portion 15. The inner leg of this bifurcated portion has side portions 17, shown extending downwardly along each equalizer bar 3 and below

2

the lower edges thereof. Each spring seat 1 is clamped in position between the bars 3 by means of a nut 19 on a clamping bolt 21 extending through transversely aligned openings in the equalizer bars 3 and between the outer and inner legs of the bifurcated clamping portion 15 of the spring seat 1. The head of a spring shackle or hanger 23 of T shape is pivoted on each clamping bolt 21 for longitudinal swinging movement between the bars 3 and within the bifurcated clamping portion of the spring seat 1. The lower end of each spring hanger 23 is shown extending downwardly through an opening in one end of another semi-elliptic truck spring 25 and an opening in a lower spring pad 27 provided with a transverse slot in the lower surface intermediate the sides which is shown resting on a spring hanger pin 29 which extends through a transverse opening in the projecting lower end of the spring hanger 23. The semi-elliptic spring 25 is accordingly hung at its ends by means of the hangers 23 adjacent the ends from and between the equalizer bars 3. To retain the spring 25 in this position in case of breakage of the ends or breakage of the spring hangers 23, or the spring hanger pins 29, a safety pin 31 is keyed in transversely aligned openings in the lower ends of the side portions 17 on the inner leg of each bifurcated portion of the spring seats 1 at a level below the ends of the spring to catch the spring adjacent the ends upon the occurrence of breakage of the above mentioned parts.

With the spring seats clamped in position to equalize the load applied thereto the integral hooks 7 on the seats 1 provide safe and convenient means whereby one man may readily attach a crane sling so that the above described equalizer assembly may be safely and quickly lifted, moved and lowered by a crane in a horizontal position for assembly between adjacent axle boxes of a railway truck.

In the modification of the invention shown in Figures 5, 6, 7 and 8 spring seats 51 of slightly different form are used. Each of the spring seats 51 differ only from those previously described by providing a side opening 53 in the central spring pocket opening 55 in place of the hook portion 7 whereby lifting hooks may likewise be conveniently attached for safe handling of the equalized assembly by a crane.

50 I claim:

1. An equalizer bar assembly for a railway truck comprising an equalizer bar and a pair of spring seats secured at longitudinally spaced points thereto, each of said seats having a spring pocket, the adjacent sides of the spring pockets

forming means for the attachment of lifting slings.

2. A spring seat for a railway truck having equalizer bars, said spring seat including side projections adapted to rest on said equalizer bars, a spring socket portion having an opening therein for the attachment of lifting means and a body portion adapted to be clamped between said equalizer bars.

3. A spring seat for a railway truck having equalizer bars, said spring seat including side projections adapted to rest on said equalizer bars, a body portion adapted to be clamped between said bars and integral hook portions to facilitate the attachment of slings for lifting.

4. A spring seat for a railway truck having laterally spaced equalizer bars, said seat having a body portion adapted to be clamped between the equalizer bars, said body portion having a spring pocket in the upper end provided with

5 opposite side projections adapted to seat on the equalizer bars and an end projection of hook form intermediate the side projections for attachment of a lifting sling.

MARTIN P. BLOMBERG.
